UNITED STATES PATENT OFFICE.

MORLAND MICHOLL DESSAU, OF LONDON, ENGLAND.

AIR BED, CUSHION, AND THE LIKE.

Application filed July 25, 1922. Serial No. 577,474.

To all whom it may concern:

Be it known that I, MORLAND MICHOLL DESSAU, a citizen of the United States of America, residing at London, England, have 5 invented Improvements in or Relating to Air Beds, Cushions, and the like, of which the following is a specification.

This invention relates to air beds, cushions and the like. Ordinarily devices of this 10 class are open to the objection that in use the support afforded is more or less of an unstable or rolling character, whilst the result of a puncture or single leak is to render the device practically valueless for the purpose intended.

To overcome these disadvantages various proposals have been made, employing a system of independently inflatable units.

The object of the present invention is to 20 provide improved forms of air bed, cushion or the like of the kind in which tubular resilient supporting units, whether they be inflatable or not, are independent of a cover and adapted to be inserted in pockets of the 25 latter which alternate with other pockets containing stuffing material serving to separate one from another.

The principal new feature of importance 30 of the present invention consists in using independent units as aforesaid enclosed in alternate pockets, each of which is of such a size and constituted by walls extending between the upper and lower layers of the covering that the presence of the units in 35 their pockets normally acts to produce a lateral compression of the stuffing material in adjacent pockets. Thus in the event of failure of any such unit, the stuffing material compressed thereby will tend to flow 40 and avoid the formation of a dead space as heretofore.

But in order that the invention may be 45 more readily understood it will now be further described with the aid of the accompanying drawings of which Fig. 1 is a plan view of a portion of a mattress showing one embodiment.

Figs. 2, 3 and 4 are views to a larger scale of details.

50 Fig. 4 represents a modification.

Fig. 5 is a part sectional side elevation corresponding to Fig. 1.

55 Figs. 6 and 7 are views illustrative of the manner of producing a filling for such a mattress.

Fig. 8 is a perspective view of a similar

mattress showing a further modification and Fig. 9 is a view showing a part of Fig. 8 in cross section.

Referring to Figs. 1 and 5 a tick *a* is subdivided by walls *b* so as to form cells for the reception of air tubes *c*, of which one is shown in Fig. 2, and also cells for the reception of a suitable stuffing *d*. In Fig. 5 an outer tick *e* is shown as separated from the inner tick *a* by a layer *f* of material at both sides of the latter.

The stuffing *d* may be of any suitable kind as already referred to but kapok will be found very suitable especially if, as shown in Fig. 6, tufts *g* thereof be interposed between two strands *h* formed of crêpe rubber appropriately twisted, the said strands being themselves subsequently twisted together as indicated more or less approximately in Fig. 7. Rubber in other forms such as the well known spongy form or soft nitrated rubber may be used as a filling not only for the cells between the tubes but also like the previously mentioned materials, for the said tubes which it then becomes optional to make air tight or not. Fig. 4 shows a tube thus filled with resilient stuffing material. In an analogous fashion hollow tubular or solid rodlike elements initially made of rubber alone or in conjunction with other materials such as the elements described with reference to Figs. 6 and 7 may be inserted between other stuffing. A mattress of such a character will be found extremely buoyant, and useful therefore as a life saver on board ship, but in this case it is desirable to arrange for a greater amount of stiffness than is naturally present. This may be achieved by embedding in the stuffing light canes *i* arranged parallel to the air tubes *c* or, as shown in Figs. 8 and 9 by longitudinal canes or stiffeners *j*. From these figures also it will be understood how a marginal tubing all round the mattress might be employed if desired.

Where transverse stiffeners such as *i* are employed the air tubes may be attached at their ends to the tick *a* so that there is a tendency to keep them in tension and produce a hammock like effect.

What I claim is: —

1. A device of the kind described comprising a cover having an upper and a lower layer of flexible material flexible walls extending between said layers dividing the same into pockets of a width approximating

- 2
- to the distance separating the layers, alternating with pockets of a much greater width, resilient tubular members independently inserted in the smaller pockets and resilient 5 stuffing material inserted in the wider pockets, substantially as described.
2. A device of the kind described comprising a cover having an upper and a lower layer of flexible material, flexible walls 10 tending between said layers dividing the same into pockets of a width approximately to the distance separating the layers, alternating with pockets of a much greater width, resilient tubular members independently inserted in the smaller pockets, resilient stuffing 15 material inserted in the wider pockets and stiffeners, arranged parallel to the pockets, embedded in said stuffing material, substantially as described.
3. A device of the kind described comprising a cover, divided transversely into pockets, stuffing material inserted in alternate pockets, resilient tubular members in adjacent pockets, transverse stiffeners embedded in the stuffing material and stiffeners arranged at longitudinal margins of the cover, substantially as described. 20
4. In a device of the kind described, a filling comprising two strands of twisted crêpe rubber, and tufts of fibre as kapok 25 interposed therebetween, the said individual strands being therewith appropriately twisted together to comprise the tufts, substantially as described. 30
- Signed at London, England, this 12th day 35 of July, 1922.

MORLAND MICHOLL DESSAU.
